U.S. PATENT DOCUMENTS

D705,678 S * 5/2014 Steffey D10/70
D822,517 S * 7/2018 Katsumi D10/106.7

FIG. 1. is a perspective view of an object detection device showing our new design;
FIG. 2. is a front view thereof;
FIG. 3. is a rear view thereof;
FIG. 4. is a left side view thereof;
FIG. 5. is a right side view thereof;
FIG. 6. is a top plan view thereof;
FIG. 7. is a bottom view thereof;
FIG. 8. is a perspective view in a first use state; and,
FIG. 9. is a perspective view in a second use state.
The broken lines shown represent portions of the object detection device and form no part of the claimed design.
